UNITED STATES PATENT OFFICE.

GEORGE V. DOHERTY, OF BOSTON, MASSACHUSETTS.

POLICE PATROL-BOX.

No. 850,910.

Specification of Letters Patent.

Patented April 23, 1907.

Application filed August 4, 1906. Serial No. 329,185.

To all whom it may concern:

Be it known that I, GEORGE V. DOHERTY, a citizen of the United States, residing at Boston, in the county of Suffolk and State of Massachusetts, have invented new and useful Improvements in Police Patrol-Boxes, of which the following is a specification.

This invention relates to an improvement in police patrol-boxes, the object of the invention being to provide a means fastened permanently to said patrol-box, whereby a prisoner may be fastened to the box by the patrolman until the patrol-wagon, with its police, arrives at the box to take the prisoner to the station-house. It often happens in cities that the patrolman after getting the prisoner to the patrol-box has a great deal of difficulty in holding him, and especially is this the case where the patrol-box is in a portion of the city inhabited by a rough element, the friends of the prisoner often taking advantage of the fact that the patrolman is busy in opening the box and telephoning to the station to attempt a rescue of the prisoner, and in such cases the patrolman is often injured by the friends of the prisoner and said prisoner escapes. To overcome this difficulty, I provide a means for attaching the prisoner to the patrol-box, said means preferably consisting of a pair of handcuffs which are attached to a movable locking member in the interior of the box by chains and are left inside the box attached to said chains, the door of the box being locked until the patrolman unlocks the box, removes one of the handcuffs, and snaps it on the prisoner's wrist. When this has been accomplished, the patrolman can telephone at his leisure to the police-station, and it will be impossible for friends of the prisoner to take him away from the patrol-box. The patrolman is provided with a key to the door of the patrol-box; but he has no key to the handcuffs which are within the box, so that friends of the prisoner could not obtain a key from the patrolman to unlock the handcuff after it had once been snapped on the prisoner's wrist. The key to unlock the handcuffs is in the possession of one of the officers who come to the assistance of the patrolman on the patrol-wagon.

It sometimes becomes desirable to take two prisoners into custody, in which case the patrolman secures the prisoner to one of the handcuffs, as hereinbefore described, and then goes in search of the second person and

having captured him takes him to the box and snaps the second handcuff onto his wrist.

The invention consists in the combination and arrangement of parts set forth in the following specification, and particularly pointed out in the claims thereof.

Referring to the drawings, Figure 1 illustrates a patrol-box in perspective with the door partly broken away and a handcuff attached to the interior of the patrol-box by means of a chain and weight. Fig. 2 is a detail section, partly broken away, taken on line 2 2 of Fig. 1 looking toward the left in said figure.

Like numerals refer to like parts throughout the several views of the drawings.

In the drawings, 4 is a patrol-box supported upon a column 5, and 6 is the door of the patrol-box. 7 7 are chains. To one end of each of said chains is attached a handcuff 8, and to the other end of each of said chains is attached a weight 9. Each of the chains 7 passes over the rear side of a flanged roll 10. The rolls 10 10 are rotatably supported upon 80 a rod 11, fastened at its opposite ends to the patrol-box. Adjacent to the rolls 10 10 is another rod 12, parallel to the rod 11 and fast at its opposite ends to the patrol-box 4. Hooks 13 13 are provided in the interior of 85 the box, upon which the handcuffs 8 8 are supported when the cuffs are not in use. In Fig. 1 one of the handcuffs is shown as supported upon its hook 13 and the other is shown as withdrawn from the box in readiness to be clasped upon the wrist of the prisoner.

The operation of the device is as follows: Assuming the handcuffs to both be hung upon their respective hooks 13 13 and the door 6 of the patrol-box closed, the patrolman when he arrives at the box with his prisoner unlocks the patrol-box door, opens the same, and taking one of the handcuffs 8 from its hook 13 draws the same outwardly, 100 causing the weight 9, attached to the chain 7, to be drawn upwardly until it is substantially in the position illustrated in Fig. 2. Any further attempt to withdraw the chain from the box will result in the weight 9 coming 105 into contact with the roll 10 and with the rod 12, which will prevent the chain and the weight from being entirely withdrawn from the patrol-box, said weight thus constituting a locking member which is movable relatively to said patrol-box. The patrolman then clasps the handcuff upon the wrist of

his prisoner. If he has more than one prisoner, he clasps one of the cuffs 8 to the wrist of each prisoner. As hereinbefore stated, if the patrolman captures but one prisoner he 5 can attach him to the patrol-box by means of the cuff and chain and then go in pursuit of another prisoner, if such there be. After attaching the prisoner to the patrol-box by means of the handcuff, chain, and weight 10 the patrolman telephones to the office, and the patrol-wagon is sent to his assistance, the handcuff being unlocked by a key in the possession of one of the patrolmen who come on the patrol-wagon.

15 Having thus described my invention, what I claim, and desire by Letters Patent to secure, is—

1. In combination, a police patrol-box, a handcuff, a chain fast at one end thereof to 20 said handcuff, and a locking member movable relatively to said patrol-box attached to the other end of said chain.

2. In combination, a police patrol-box, a handcuff, a chain fast at one end thereof to 25 said handcuff, a weight fast to the other end of said chain, and means to guide said chain.

3. In combination, a police patrol-box, a handcuff, a chain fast at one end thereof to said handcuff, a weight fast to the other end

of said chain, and a roll journaled to rotate 30 upon said patrol-box adapted to guide said chain.

4. In combination, a police patrol-box, a handcuff, a chain fast at one end thereof to 35 said handcuff, a weight fast to the other end of said chain, a roll journaled to rotate upon said patrol-box adapted to guide said chain, and a rod fast to said box adjacent to said roll adapted to prevent the withdrawal of said chain and weight from said box. 40

5. In combination, a police patrol-box, a handcuff, a chain fast at one end thereof to 45 said handcuff, a weight fast to the other end of said chain, a roll journaled to rotate upon said patrol-box adapted to guide said chain, a rod fast to said box adjacent to said roll adapted to prevent the withdrawal of said chain and weight from said box and a hook fast to said box upon which said handcuff 50 may be supported.

In testimony whereof I have hereunto set my hand in presence of two subscribing witnesses.

GEORGE V. DOHERTY.
